ROTARY PAINTING MECHANISM

Filed April 10, 1929

FIG. 1.

FIG. 2.

INVENTOR.

CHARLES A. WOOD

BY

Byron D. Cohn.

ATTORNEY.

UNITED STATES PATENT OFFICE

CHARLES A. WOOD, OF CLAY CENTER, KANSAS

ROTARY PAINTING MECHANISM

Application filed April 10, 1929. Serial No. 354,086.

My invention relates to a mechanism for applying paint, lacquer and the like to the rims of wheels for toys.

The object of my invention is to provide a painting machine arranged to color the rims of wheels for toys by means of a rotating cylinder covered with felt or a like substance having its lower portion submerged in a reservoir of paint in order that a plurality of wheels, fabricated for use on toys, trunnioned on a rod, may be painted by pressing the same against the felt surface of the cylinder.

A still further object of my invention is to provide a rotary cylindrical painting mechanism comprising a cylinder covered with felt or a like material trunnioned on the sides of a reservoir and having its lower portion submerged in the paint contained therein and the amount of paint applied to the articles pressed against the surface of the cylinder determined by the pressure of an adjustable brush acting against the felt to wipe off surplus paint.

A still further object of my invention is to provide cup-like members on the ends of the cylinder of the mechanism described, the cup-like members being formed in the manner of a truncated cone to prevent the paint or lacquer from entering the bearings.

A still further object of my invention is to provide a mechanism of the kind described capable of painting or lacquering a plurality of toy wheels positioned on a rod in a quick and economical manner.

These and other objects will be hereinafter more fully explained, reference being had to the accompanying drawings forming a part of this specification in which like characters will apply to like parts in the different views.

Referring to the drawings:

Fig. 1 is an end view of the painting machine and the end of a plurality of toy wheels positioned against the felt surface of the cylinder.

Fig. 2 is a plan view of the painting machine with the cover plate removed and showing a plurality of wheels held against the felt surface of the cylinder.

50 A cylinder 1 having a spindle 2 is trun-

nioned in the bearings 3 and 4, the latter being affixed to the walls of a reservoir 5 as shown. The pulley 6 rigidly positioned on the spindle 2 provides a means of rotating the cylinder by belt drive from a motor or line shaft. A felt covering 7 is firmly affixed to the surface of the cylinder. The lower portion of the cylinder is submerged in the paint or lacquer contained in the reservoir 5, the level of which is designated by the dotted line at A in Fig. 1. A brush 8 is pivotally carried by the threaded pins 10 and 11 on the sides of the reservoir 5 in the manner shown. The knurled nuts 10' and 11' threadedly engaging the pins 10 and 11 respectively, function to clamp the yoke 9 in the desired position. The bristles 12 of the brush rest, at their outward extremity, on the felt surface 7 of the cylinder as shown at B. The pressure of the bristles against the felt surface is determined by the position of the yoke 9.

The function of the engagement of the bristles of the brush with the surface of the cylinder is to regulate the saturation of the felt covering 7 as it rotates toward the wheels 13. The action of the brush also prevents an excess amount of paint being applied to the wheels 13. The excess paint withheld by the brush action returns to the contents of the reservoir as the cylinder rotates.

The wheels 13 represent in this instance those used on toys of a miniature nature simulating automotive vehicles. The wheels are trunnioned on a rod 14 which is held in the hands of the operator at C and D and the peripheries or rims of the wheels are pressed simultaneously, by this arrangement, against the felt covering 7 and a coating of paint or lacquer is applied, giving the wheels the appearance of having tires. The depth of the painting area on the wheel is determined by the pressure applied by the operator and the thickness of the felt covering. In order to prevent the flow of paint or lacquer from the ends of the cylinder into the bearings 3 and 4, I have provided the guards 15 and 16 formed in the shape of a hollow truncated cone and placed concentric to the axis of rotation of the cylinder as illustrated. A lid or cover 17 acts as a baffle for the spray of

paint or lacquer that may originate from the action of the cylinder in the reservoir.

I have found that the painting mechanism herein described is very effective and quick 5 in the application of paint to the toy wheels herein described. It is also economical in the use of paint with regard to the amount of work handled.

Such modifications may be employed as 10 lie within the scope of the appended claims and what I do claim as new and desire to secure by Letters Patent is:

1. In a power driven rotary painting mechanism for toy wheels the combination of a 15 rod, a rotary cylinder positioned on the sides of a box-like structure containing painting fluid and an adjustable brush affixed to the walls of the said structure and having its bristles in slidable contact with the surface of 20 the cylinder, the rod carrying a plurality of toy wheels rotatably positioned thereon and held in rotatable contact with the surface of the cylinder, the said cylinder having its lower portion submerged in a painting fluid 25 contained in the reservoir of the structure and the said brush member having its bristles in engagement with the surface of the cylinder to wipe off excess paint carried by the cylinder in the application of paint to the 30 peripheries of the toy wheels.

2. In a coating device for applying paint to the rims of a plurality of miniature wheels, in combination, a rod rotatably carrying a 35 number of the wheels, a drum having a felt covering, a reservoir and a brush, means to rotate the drum, the brush distributing paint over the felt covering on the drum and the rod placed to allow contact of the wheels with the felt covering.

40 In testimony whereof I affix my signature.

CHARLES A. WOOD.
